Primary Examiner — Dana Meyrow(74) *Attorney, Agent, or Firm* — The Belles Group, P.C.(57) **CLAIM**

The ornamental design for a bottle, as shown and described.

DESCRIPTION

FIG. 1 is a front perspective view of a bottle according to the new design;

FIG. 2 is a front elevation view thereof, the rear elevation view being identical to the front elevation view;

FIG. 3 is a left side elevation view thereof, the right side elevation view being identical to the left side elevation view;

FIG. 4 is a top plan view thereof; and,

FIG. 5 is a bottom plan view thereof.

The bottle is transparent. The details of the opposing side of the bottle as they would be seen through the transparent sidewall material has been omitted from the drawing views for ease of understanding.

The broken lines in the drawings illustrate portions of the bottle that form no part of the claimed design.
